(57) **CLAIM**

The ornamental design for a face plate of a control panel for a paver fire pit, as shown and described.

DESCRIPTION

FIG. 1 is a perspective view of a face plate of a control panel for a paver fire pit.

FIG. 2 is another perspective view of the face plate.

FIG. 3 is a front view of the face plate.

FIG. 4 is a rear view of the face plate.

FIG. 5 is a left side view of the face plate.

FIG. 6 is a right side view of the face plate.

FIG. 7 is a top view of the face plate; and,

FIG. 8 is a bottom view of the face plate.

The broken lines in the drawings illustrate portions of the face plate of a control panel for a paver fire pit, and form no part of the claimed design.
